CLAIM

The ornamental design for a combined fluid alert and thermometer, as shown and described.

DESCRIPTION

FIG. 1 is a top plan view of a combined fluid alert and thermometer showing my new design;

FIG. 2 is a bottom elevational view;

FIG. 3 is a left side elevational view, the right side elevational view being a mirror image;

FIG. 4 is a rear elevational view; and

FIG. 5 is a front elevational view thereof.

FIG. 1

FIG. 2

FIG. 3

FIG. 4

FIG. 5
